UNITED STATES PATENT OFFICE.

OTTO J. MONSON, OF CHICAGO, ILLINOIS.

FLOSS-HOLDER ATTACHMENT FOR TOOTH-BRUSHES.

No. 893,845.

Specification of Letters Patent.

Patented July 14, 1908.

Application filed July 16, 1907. Serial No. 384,024.

To all whom it may concern:

Be it known that I, OTTO J. MONSON, a citizen of the United States, residing at Chicago, in the county of Cook and State of Illinois, have invented new and useful Improvements in Floss - Holder Attachments for Tooth-Brushes, of which the following is a specification.

This invention relates to a floss holder for holding a piece of floss or other thread whereby the spaces between the teeth can be readily and conveniently cleaned.

The invention has for one of its objects to provide a floss holder which can be used as an attachment for a tooth brush by applying the same to the handle thereof.

A further object is the provision of a floss holder comprising a strip of metal bent into suitable shape and having spring jaws at its ends for receiving the ends of the floss or thread, the holder being pivotally mounted on a handle.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates certain of the embodiments of the invention, Figure 1 is a side view of a tooth brush provided with the floss holder attachment. Fig. 2 is a side view of the floss holder provided with a handle. Fig. 3 is a plan view. Fig. 4 is a perspective view of the floss holder detached and drawn on an enlarged scale. Fig. 5 is a sectional view on line 5—5, of Fig. 4.

Similar reference characters are employed to designate corresponding parts throughout the several views.

Referring to the drawing, 1 designates the handle of an ordinary tooth brush to which is attached at its outer end the floss holder designated generally by A. This holder preferably comprises a strip of spring metal 2 bent into U-shape and having its ends formed into spring jaws 3 by bending the extremities of the strip backwardly against the outside of the arms 4. The bends 5 are provided with notches 6 for receiving the thread of floss 7 and prevent the latter from becoming displaced while in use, the ends of the thread being brought downwardly over the

outside of the spring jaws 3 and then under the same so as to be clamped as shown in Fig. 4. The base portion of the strip 2 has a central aperture 8 for the reception of a pivot 9 for attaching it to the handle of the tooth brush 60 or a separate handle 10, as shown in Fig. 2. This pivot may take the form of a rivet as shown in Fig. 2 or a bolt having a nut 11 as shown in Fig. 1, so as to permit the holder to be changed from one side of the handle 1 to 65 the other to suit the fancy of the user. The floss holder is free to turn on the pivot so as to readily adapt it to the back, as well as the front, teeth. The ends 3 of the metal strip are reduced in width, as shown in Fig. 4 so as 70 to bring the side edges thereof nearer in line with the notches 6, thus admitting of easy application of the floss into the clamps. One edge of each of the jaws 3 is sharpened at 12, Figs. 4 and 5, so that the floss can be cut 75 thereby.

In practice the end of a spool of floss is inserted under one of the jaws 3 with a slight portion extending therefrom so that it can be taken hold of when it is desired to remove 80 the floss. The spool is unwound and the floss stretched across the holder to the other jaw or clamp 3, care being taken to place the floss in the notches 6. After the floss is engaged under the second jaw a strong pull is 85 exerted in a direction to cause sharp edge 12 to sever the floss close to the jaw and without waste. With the floss thus held taut the cleaning of the teeth is accomplished by inserting the floss between two adjacent teeth 90 and imparting a reciprocating motion, thereby dislodging any matter accumulated between the teeth. All the teeth are cleaned in this manner and when it is desired to take out the floss, the ends of the floss are disengaged from the jaws so that a new piece can 95 be substituted.

From the foregoing description, taken in connection with the accompanying drawings, the advantages of the construction and of the 100 method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are 105 within the scope of the claims. 110

Having thus described the invention, what I claim is:—

1. A device of the class described comprising a handle, a pivot thereon, and a thread holding element mounted to turn on the pivot, said element comprising a single piece of metal bent into spaced arms and having its extremities bent backwardly with respect to the arms to form thread holding clamps, thread cutting means on the said extremities, and means on the ends of the arms for holding the thread from slipping laterally off the latter.
2. A device of the class described comprising a handle, a single piece of metal bent into a U-shaped structure and having its extremities bent backwardly to form spring clamps,

the bends of the metal being notched to receive a thread, the edges of the backwardly-bent extremities being sharpened to form knife edges.

3. A device of the class described comprising a handle, a strip of metal having spaced arms and bent at its extremities to form spring clamps, the bends of the strip being provided with notches, and a thread engaged in the notches and having its ends secured by the clamps.

In testimony whereof, I affix my signature in presence of two witnesses.

OTTO J. MONSON.
